UNITED STATES PATENT OFFICE

163,501

GARDEN TOOL

Eugene C. Weidig, New Orleans, La.

Application February 1, 1951, Serial No. 14,073

Term of patent 14 years

(Cl. D35—2)

To all whom it may concern:

Be it known that I, Eugene C. Weidig, a citizen of the United States and a resident of New Orleans, in the county of Orleans and State of Louisiana, have invented the new, original, and ornamental Design for a Garden Tool, of which the following is a specification, reference is had to the accompanying drawings, forming part thereof, in which:

Figure 1 is a side elevational view of a garden tool, showing my new design.

Figure 2 is a bottom view.

Figure 3 is an end elevational view.

Figure 4 is a plan view.

I claim:

The ornamental design for a garden tool, as shown.

EUGENE C. WEIDIG.
